UNITED STATES PATENT OFFICE.

GEORGE UNTCH, OF CLEVELAND, OHIO.

HASP-FASTENER.

1,017,709.

Specification of Letters Patent. Patented Feb. 20, 1912.

Application filed October 16, 1911. Serial No. 654,850.

To all whom it may concern:

Be it known that I, GEORGE UNTCH, a citizen of the United States, residing at Cleveland, in the county of Cuyahoga and State 5 of Ohio, have invented certain new and useful Improvements in Hasp-Fasteners, of which the following is a specification.

This invention relates to hasp fasteners and has for its object to provide improved 10 means for fastening or locking a hasp against unauthorized opening.

The invention is illustrated in the accompanying drawings in which—

Figure 1 is a front elevation of the device. 15 Fig. 2 is a section on the line 2—2 of Fig. 1. Fig. 3 is a section on the line 3—3 of Fig. 1. Fig. 4 is a rear elevation, in reverse of Fig. 1. Fig. 5 is a front elevation of a modification, including a lock. Fig. 6 is a detail 20 in front elevation of the lock. Fig. 7 is a rear elevation of the lock. Fig. 8 is a section on the line 8—8 of Fig. 5.

Referring specifically to the drawings, 6 is a staple plate fastened to the door jamb, 25 provided with a staple or the like 14 which has a hole 20 to receive a padlock or the like if desired.

7 is the hasp plate, hinged at 9 to the plate 8 fastened to the door, and this hasp has a 30 hole 14^a to receive the staple 14. The hasp is offset outwardly to provide space behind the same for the latch plate 10 which is pivoted to the hasp by a pin 11, so as to swing vertically. The extent of its swing is limited 35 by a pin 22 projecting on the back of the hasp, working in a slot 13, or by a rib 23, formed on the back of the hasp, projecting into a notch 24. The outer end of the latch plate 10 is curved as at 16 to hook over the 40 end of the hasp, and it is recessed to form a tongue 15, with a hole 17, the tongue being adapted to drop into an opening 21 in the staple, so that the latch pin 18 will engage in said hole and so prevent lift of the plate. 45 The pin 18 is carried by a flat spring 18^a which is fastened to the underside of the staple plate 6 and works in a recess behind the same. A push pin 18^b is attached to the

spring, and when pushed in it will withdraw the pin 18 from the hole 17, permitting 50 the latch plate to be lifted and allowing the hasp to be swung off the staple.

For use with a lock, the structure is modified as shown in Figs. 5 to 8, wherein a lock 28 is embedded in the jamb, and has a bolt 55 27 which may be shot to engage under the pin 18, as shown in Figs. 7 and 8, and when so engaged it is impossible to press in the push pin 18^b, the parts being locked against movement, but by withdrawing the bolt, as 60 with a key inserted in the key hole 29, the pin 18^b may be pushed in to withdraw the latch pin 18 from the latch plate. To conceal the key hole I provide a swinging guard 25 which is pivoted at 26^a on the front of 65 the lock, and when swung down it covers the key-hole. 26 is a stop pin for the guard, which pin strikes into a notch 26^b when the guard is swung down.

I claim:

1. The combination with a hasp and staple, of a latch plate pivoted to the back of the hasp and having a tongue engageable in an opening in the staple, a spring latch pin located behind the staple and engageable with said tongue, and means to disengage the latch pin. 75

2. The combination with a hasp and a staple and a plate from which the staple projects, of a latch plate pivoted to the back 80 of the hasp and having a tongue engageable in an opening in the staple, in front of the plate, a latch pin working through said plate behind the staple to engage said tongue, a spring located behind the plate and connected to the pin and tending to advance the same, and a push pin connected to the spring 85 to disengage the latch pin.

3. The combination of a hasp and staple, a latch plate pivoted to the back of the staple 90 and having a tongue engageable in the staple, a latch pin movable in and out behind the staple to engage or disengage the tongue, and means to lock the latch pin against movement. 95

4. The combination of a hasp, a plate hav-

ing a staple projecting therefrom to engage the hasp, a latch plate pivoted to the back of the hasp and having a tongue engageable with the staple, a latch pin working through the plate and engageable with the tongue, means to disengage the latch pin, and means to lock the latch pin against movement comprising a lock having a bolt working under

said plate and which may be advanced to engage behind the latch pin.

In testimony whereof, I do affix my signature in presence of two witnesses.

GEORGE UNTCH.
